UNITED STATES PATENT OFFICE.

JOHN W. BRITTIN, OF BLACK ROCK, CONNECTICUT.

BIT-STOCK.

SPECIFICATION forming part of Letters Patent No. 241,920, dated May 24, 1881.

Application filed February 28, 1881. (No model.)

To all whom it may concern:

Be it known that I, JOHN W. BRITTIN, a citizen of the United States, residing at Black Rock, in the county of Fairfield and State of Connecticut, have invented new and useful Improvements in Bit-Stocks, of which the following is a specification.

This invention relates to that class of bit-stocks comprising a slotted tube open at one end, a bit-socket arranged in the tube, and a set-screw projecting through the slot of the tube for clamping the bit-socket in the desired position, the extent to which the bit projects from the tube determining the depth of the hole that is bored by its means.

My invention consists in the arrangement of an annular rotating head on the open end of the tube, for the purpose of avoiding injury to the surface of the wood by the contact of the tube with it. The rotating head is provided with side openings for the escape of wood-cuttings.

It also consists in the arrangement of screws in the tube for the purpose of steadyng the bit; further, in a certain novel construction of the bit-socket, hereinafter fully explained.

This invention is illustrated in the accompanying drawings, in which Figure 1 represents a longitudinal section. Fig. 2 is a cross-section on the line *xx*, Fig. 1. Fig. 3 is a similar section on the line *yy*, Fig. 1.

Similar letters indicate corresponding parts.

The letter *A* designates the tube; *B*, its slot; *C*, the bit-socket, and *D* the set-screw for the socket. The slot *B* extends nearly the entire length of the tube *A*, and the latter is open at one end, the other end thereof being closed, and being provided with a polygonal head, *5*, for its engagement with a brace. The bit-socket *C* is constructed to receive the tail end of the bit, (marked *E*), and it is set by the screw *D* (which projects through the slot *B*) to retain the bit in the desired position.

When the bit is applied to use the lower or open end of the tube *A* comes in contact with the surface of the wood, thus determining the depth of the hole; and in order to avoid injury to the wood by such contact I arrange on the open end of the tube an annular head, *F*, which is capable of rotating thereon, or, in other words, allowing a rotary motion of the tube

independently thereof. This rotating head *F* thus is the part of the tube coming in contact with the wood, and inasmuch as the head at once remains stationary upon its surface this surface is left uninjured thereby. I prefer to make the head *F* to flare in a downward direction away from the tube in order to obtain a broad base, and its connection with the tube is effected by means of screws *6* passing radially through the head and entering a circumferential groove, *7*, in the tube. When the head *F* approaches the wood a portion of the cuttings enter the head, and to permit their escape therefrom the head is provided with side openings, *8*, of suitable size and shape.

When the lower part or shank of the bit *E* is left unsustained in the tube it is liable to shake or become thrown out of the center, and to avoid this danger I make use of screws *G*, which pass radially through the side of the tube and impinge against the bit at their inner ends, thus effectually steadyng the bit. These screws *G* are simply retracted when it is desired to change the position of the bit, and then again forced up against it.

The bit-socket *C* is divided into two parts, and an eye, *H*, formed on the shank of the set-screw *D*, is fitted on it. This eye *H* is held by or between a shoulder, *10*, formed on the socket, and a ring, *I*, which is attached to the socket by a screw, *J*, passing through the ring and through both parts of the socket. This screw *J* thus serves not only to retain the ring *I* in its position, but also to connect the divisions of the socket in a longitudinal direction. The inner diameter of the eye *H* and ring *I* is larger than the outer diameter of the socket opposite to these parts, and by this arrangement the divisions of the socket are allowed to separate to a sufficient extent for the removal of the bit, while when the set-screw *D* is tightened the eye tends to compress such divisions on the bit. The screw *D* is set by a thumb-nut, *9*, having a suitable washer interposed between it and the tube.

What I claim as new, and desire to secure by Letters Patent, is—

1. The tube *A*, having at its lower open end the loosely-attached rotary head *F*, and at its upper end the angular head for connecting it with an ordinary brace, said tube and head

being constructed to surround the bit when in use, substantially as described, for the purpose set forth.

2. The combination, with the tube A, having means to connect it with a brace, and provided on its interior with an adjustable bit-socket, of an annular rotary head, F, loosely connected with the open lower end of the tube, through which the bit extends and rotates independently of said head, substantially as described, for the purposes set forth.

3. The slotted tube, having at its lower open end an annular rotating head provided with side openings, in combination with the bit-socket and its set-screw, said tube and head surrounding the bit, substantially as and for the purpose described.

4. The slotted tube provided with bit-steady-

ing screws, in combination with the bit-socket and its set-screw, all arranged for use substantially as described.

5. In combination with the slotted tube A, the bit-socket C, composed of two vertical sections having shoulders 10, the stationary ring I, and the set-screw D, having the eye II arranged upon the socket between the shoulders and the ring, substantially as and for the purpose described.

In testimony whereof I have hereunto set my hand and seal in the presence of two subscribing witnesses.

JOHN W. BRITTIN. [L. S.]
